UNITED STATES PATENT OFFICE.

EMIL A. KREVIS, OF CHICAGO, ILLINOIS.

TIE-HOLDER.

1,019,489.

Specification of Letters Patent.

Patented Mar. 5, 1912.

Application filed May 17, 1911. Serial No. 627,680.

To all whom it may concern:

Be it known that I, EMIL A. KREVIS, a citizen of the United States, and a resident of the city of Chicago, county of Cook, and 5 State of Illinois, have invented certain new and useful Improvements in Tie-Holders, of which the following is a specification.

My invention relates to improvements in tie-holders and has for its object the 10 provision of a device of this character which shall be of neat and simple design and suitable for advertising purposes.

A further object of my invention is to provide an advertising device of the character stated which shall be so constructed 15 as to be foldable into a compact form for transportation purposes.

Other objects will appear hereinafter.

With these objects in view my invention 20 consists in the novel construction and arrangement of parts all as will be herein-after more fully described and particularly pointed out in the appended claims.

My invention will be more readily understood by reference to the accompanying 25 drawing forming a part of this specification, and in which,

Figure 1 is a perspective view of a tie-holder embodying my invention, the same 30 being shown in extended condition, and Fig. 2 is an end elevation of the tie-holder showing the same in folded condition.

The preferred form of construction of my invention as illustrated in the accompanying 35 drawings comprises a plurality of elongated parallel compartments 1 formed from an elongated rectangular blank of paper or card-board. The bottom of each compartment 1 is provided with a score 2 which 40 runs transversely of the blank and longitudinally of its respective compartment. The object of the score 2 is to render the bottom foldable, said score being midway between the sides or walls of the compartment and dividing the bottom into two equal 45 parts. The blank is also provided with transverse scores 3, the partitions 4 between the compartments being formed by bending the blank along the scores 3 and by pasting 50 together the contiguous walls formed thereby, this construction being clear by reference to Fig. 1. The lower edge of each wall composing a partition 4 is also scored in order to facilitate the folding of the device. It is apparent from the construction 55 shown that the partitions are double-walled

and that the exterior walls 5 of the outermost compartments are of but a single thickness and consequently of less stiffness or strength than said partitions. In order 60 to reinforce the walls 5 and to cause them to assume a vertical or perpendicular position as shown in Fig. 1 pliable metallic clips 6 are provided and pasted or otherwise secured centrally on the exterior surface 65 of said walls 5, the object of the pliability of said clips being that they may be bent into any desired form. Thus in the extended condition as shown in Fig. 1 the clips 6 are bent into right angular form 70 and when the device is folded as shown in Fig. 2 said clips are bent from the right angular form as indicated by dotted lines into the full line positions whereby the parts of the device are held together for 75 transportation and advertising purposes. The exterior surface of the walls 5 will obviously be exposed when the device is folded, hence this surface is utilized for advertisements as indicated in Fig. 1. Each 80 compartment of the device is of sufficient capacity to hold one or more ties 7 which are preferably positioned therein as shown in Fig. 1. It is understood that the device is placed horizontally upon a table or 85 dresser, so that no means other than gravity is necessary for holding the ties 7 in place in the compartments.

A tie-holder or advertising device of the construction set forth is neat of appearance 90 and when folded is suitable for transportation or advertising purposes.

While I have illustrated and described the preferred form of construction for carrying my invention into effect, this is capable of 95 variation and modification without departing from the spirit of the invention. I therefore do not wish to be limited to the precise details of construction set forth, but desire to avail myself of such variations and 100 modifications as come within the scope of the appended claims.

Having described my invention what I claim as new and desire to secure by Letters Patent is:

1. A device of the class described comprising a series of elongated parallel compartments formed from an elongated rectangular blank scored transversely, the partitions between the compartments being 110 double-walled and formed by bending said blank along the scores thereof, and metallic

reinforcing clips provided on the exterior walls of the outermost compartments, substantially as described.

2. A device of the class described comprising a series of elongated parallel compartments formed from an elongated rectangular paper blank scored transversely, the partitions between the compartments being double-walled and formed by bending said blank along the scores thereof, the walls of said partitions being pasted together, and pliable metallic reinforcing clips provided

on the exterior walls of the outermost compartments, said clips being centrally positioned on their respective walls, substantially as described. 15

In testimony whereof I have signed my name to this specification in the presence of two subscribing witnesses.

EMIL A. KREVIS.
